ELECTRIC WELDER

Earl S. Taylor, Detroit, Mich., assignor to Swift
Electric Welder Company, Detroit, Mich., a cor-
poration of Michigan

Application April 27, 1936, Serial No. 76,706

6 Claims. (Cl. 219—4)

The invention relates to electric welders of that type known as "gun welders" and comprising a pair of electrodes mounted on a portable tool and pressed towards each other against the 5 intervening work by fluid pressure. The welding current is conveyed to the tool through cables and the pressure fluid through a connecting hose, these parts being sufficiently flexible. There is also a handle connected with the cylinder of the 10 fluid motor for actuating the movable electrode and a yoke connecting with the stationary electrode which provides clearance for the insertion of the work.

In the use of tools of this type the flexibility of 15 the cables and hose will permit the workman to adjust the tool to different positions upon the work, but difficulty is sometimes encountered through interference of the yoke. Thus, in going from one side to another of the work, it is necessary to twist the tool to bring the yoke in 20 proper position and in doing so considerable effort is required of the operator to overcome the resistance of the cables. It is the object of the present invention to overcome this difficulty 25 through a construction permitting of the rotation of the yoke without the necessity of twisting the portion of the tool to which the cables and hose are connected. The invention, therefore, 30 consists in the novel construction as hereinafter set forth.

In the drawing:

Figure 1 is a central longitudinal section through my improved tool;

Figure 2 is an end elevation thereof;

Figure 3 is a cross-section on line 3—3 of Figure 1.

My improved tool comprises a cylinder A containing a piston B connected to the rod C which passes out through an aperture in the head D and carries at its outer end the fitting E for holding the electrode F. The cooperating electrode G is arranged in alignment with the electrode F and engages a C-shaped yoke H which is mounted on the head D. A handle I projects laterally 45 from the cylinder A being preferably integral therewith and an electric push button switch J is mounted in this handle for convenient operation. This switch controls an electrically operated valve (not shown) which supplies the fluid 50 to the cylinder A through a hose K connected to the nipple A'. The piston B is formed of a dielectric material, such as bakelite, and the sealing cup B' is also a non-conductor. The rod C is also insulated from the cylinder by passing 55 out through an insulator bushing L in the head

D. Current is supplied to the tool through cables respectively connected to a nipple A² on the cylinder A and a nipple E' on the fitting E. Thus the electrodes F and G and their connecting parts are insulated from each other so that the 5 only path of the current will be through the work inserted between these electrodes.

The tool as thus far described is similar to constructions that have heretofore been used with the exception of the manner of connecting the 10 yoke H with the head D. As heretofore constructed, the yoke is rigid with the frame of the tool so that in passing from one side to an opposite side of the work, it is necessary to twist the tool and its connecting cables. My improved 15 construction avoids this necessity by revolutely mounting the yoke upon the head D. However, as the current is conducted through the yoke to the electrode G it must pass through the swivel 20 joint between said yoke and the head D. To provide for this, I devise the following construction:

The head D has projecting therefrom an extension D' which at its outer end has a flange M. As specifically shown, the extension D' is integral with the head D and the flange M is secured thereto by a threaded hub portion M' engaging a threaded extension D² of reduced diameter. The yoke H is swiveled upon the portion D', preferably with an intervening roller bearing 25 N and is retained by the flange M. The rolls 30 of the roller bearing are formed of a highly conductive material, such as bronze, which reduces the ohmic resistance to the passage of current therethrough and which also is non-magnetic to avoid any magnetic resistance. The annular 35 portion H of the yoke which surrounds the portion D' is preferably provided with a bushing N' and a sleeve N² surrounds the portion D'. These members are proportioned to form a fairly tight fit so as to maintain good electrical contact for the flow of current therethrough. Thus, 40 the yoke is retained in position by the flange member M and is free to be revolved by reason of the roller bearings, while at the same time current is conveyed from the nipple A² through the roller bearing to the yoke and thence to the electrode G. A metallic bushing O is placed between the rod C and the insulator bushing, and the cylinder A is preferably provided with a bushing A³ which may be replaced to compensate for wear. A spring P normally retracts the piston B to separate the electrodes G and F, while the fluid pressure controlled by the switch J is used to press the electrode F against the work.

With the construction as described, the op-

erator can turn the yoke H independently from any rotation or twisting of the tool which facilitates the performance of the work and lessens effort on the part of the workman.

5. What I claim as my invention is:

1. An electric welder of the gun type including a handled member, a cable connection, a yoke for embracing the work and a swivel connection between said yoke and cable connection permitting rotative adjustment of one relative to the other.

2. An electric welder of the gun type including a handled member carrying the presser electrode, a yoke for embracing the work and carrying the 15 cooperating electrode, a cable connection and swivel means interposed between said cable connection and yoke permitting rotative adjustment of one relative to the other.

3. An electric welder of the gun type including 20 a handled member, a presser electrode carried thereby, fluid actuating means for said presser electrode, a fluid supply conduit extending to a source of fluid under pressure, cable connections respectively to said handled member and electrode, a yoke for embracing the work and supporting a cooperating electrode and a swivel connection between said yoke and handled member 25 permitting relative rotative adjustment thereof and also constituting an electrical connection 30 therebetween.

4. An electric welder of the gun type including a handled member, a presser electrode carried thereby and insulated therefrom, cable connections to said presser electrode and said handled member, a cooperating electrode, a yoke for sup-

porting said cooperating electrode spaced from said presser electrode and adapted to embrace the work, and a swivel connection between said yoke and handled member permitting relative rotative adjustment thereof and also constituting 5 an electrical connection therebetween.

5. An electric welder of the gun type comprising a fluid cylinder, a handle connected thereto, a piston in said cylinder, an electrode actuated by said piston and insulated from said cylinder, 10 cable connections between a source of electrical current and said electrode and cylinder respectively, a flexible conduit for conveying fluid from a source of supply to said cylinder, a cooperating electrode spaced from said first mentioned 15 electrode, a yoke for supporting said cooperating electrode and adapted to embrace the work, and a swivel connection between said yoke and said cylinder constituting also an electrical connection therebetween.

6. An electric welder of the gun type comprising a fluid motor cylinder, a piston therein, an electrode actuated by said piston and insulated from said cylinder, a fluid supply conduit for said cylinder, cable connections between a source 25 of electrical current and said electrode and cylinder respectively, an extension of said cylinder, a yoke having an annular portion surrounding said extension, a roller bearing between said extension and yoke constituting a swivel and also 30 an electrical connection therebetween and a cooperating electrode carried by said yoke in spaced relation to said first mentioned electrode.

EARL S. TAYLOR.
